MOLAR ORTHODONTIC BASE

Kozo Kawaguchi, Ohkuma-machi, Japan, assignor to
G.A.C. International, Inc., Farmingdale, N.Y.

Filed July 30, 1975, Ser. No. 600,356

Term of patent 14 years

Int. Cl. D24—03

U.S. Cl. D24—1 C

Fig. 1.

Fig. 2.

Fig. 3.

Fig. 6.

Fig. 4.

Fig. 5.

FIG. 1 is a perspective view of the lower molar orthodontic base showing my new design;

FIG. 2 is a top plan view of the orthodontic base of FIG. 1;

FIG. 3 is a side elevation view of the orthodontic base of FIG. 1;

FIG. 4 is a front elevation view of the orthodontic base of FIG. 1;

FIG. 5 is a cross-sectional elevation view taken along the line 5-5 of FIG. 2;

FIG. 6 is a cross-sectional elevation view taken along the line 6-6 of FIG. 2;

FIG. 7 is a perspective view of a modified embodiment of an upper molar orthodontic base showing my new design;

FIG. 8 is a top plan view of the orthodontic base of FIG. 7;

FIG. 9 is a side elevation view of the orthodontic base of FIG. 7;

FIG. 10 is a front elevation view of the orthodontic base of FIG. 7;

FIG. 11 is a cross-sectional elevation view taken along the line 11-11 of FIG. 8; and

FIG. 12 is a cross-sectional elevation view taken along the line 12-12 of FIG. 8.

I claim:

The ornamental design for a molar orthodontic base, as shown and described.
